CLAIM

The ornamental design for a cartridge-based electronic game housing, as shown and described.

DESCRIPTION

FIG. 1 is a top left perspective view of a cartridge-based electronic game housing showing my new design; FIG. 2 is a left side elevational view of the electronic game of FIG. 1, the right side elevational view being identical;

FIG. 3 is a top plan view of the electronic game of FIG. 1;

FIG. 4 is a front elevational view of the electronic game of FIG. 1;

FIG. 5 is a rear elevational view of the electronic game of FIG. 1; and

FIG. 6 is a bottom plan view of the electronic game of FIG. 1.
